TELEPHONE TALK-LINE MONITORING SWITCH ASSEMBLY

Paul V. De Luca, Port Washington, and William V. Carney, Valley Stream, N.Y., assignors to Porta Systems Corp., Roslyn, N.Y.

Filed July 27, 1971, Ser. No. 166,654

Term of patent 14 years

Int. Cl. D14—03; D13—03
U.S. Cl. D26—14 A

FIG. 1 is a perspective view of the telephone talk-line monitoring switch assembly embodying our new design;

FIG. 2 is a front view of the assembly depicted in FIG. 1;

FIG. 3 is a side view of the assembly shown in FIG. 1;

FIG. 4 is a top plan view of the assembly depicted in FIG. 1; and

FIG. 5 is a rear view of the telephone talk-line monitoring switch assembly depicted in FIG. 1.

We claim:

The ornamental design for a telephone talk-line monitoring switch assembly, substantially as shown.
